(57) **CLAIM**

The ornamental design for a bicycle wheel light assembly, as shown and described.

DESCRIPTION

FIG. 1 is a top plan view of a bicycle wheel light assembly according to the design;

FIG. 2 is a bottom plan view thereof;

FIG. 3 is a right side elevational view taken along line 3-3 as shown in FIG. 1;

FIG. 4 is a left side elevational view taken along line 4-4 as shown in FIG. 1;

FIG. 5 is a front elevational view taken along line 5-5 as shown in FIG. 1;

FIG. 6 is a rear elevational view taken along line 6-6 as shown in FIG. 1;

FIG. 7 is a front elevational view taken along line 7-7 as shown in FIG. 1;

FIG. 8 is a cross-sectional view taken along line 8-8 as shown in FIG. 1;

FIG. 9 is a rear elevational view taken along line 9-9 as shown in FIG. 1; and,

FIG. 10 is a cross-sectional view taken along line 10-10 as shown in FIG. 1.

The battery portion in FIGS. 3 through 6 and the light coil element in FIGS. 7 through 9 have been shown separately for ease of illustration.

The broken lines shown in FIGS. 1, 2 and 6 illustrate environmental subject matter only and form no part of the claimed design.

The light coil element is shown with a symbolic break in its length. The appearance of any portion of the article between the break lines forms no part of the claimed design.
